(57) **CLAIM**

The ornamental design for a decorative corner stand, as shown and described.

DESCRIPTION

FIG. 1 is a perspective view of the decorative corner stand of the invention;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines are for the purpose of illustrating the environment of the article only and form no part of the claimed design.
